UNITED STATES PATENT OFFICE.

JAMES J. QUINN, OF EDDYSTONE, PENNSYLVANIA, ASSIGNOR TO WILBUR A. HAWK,
OF DARBY, PENNSYLVANIA.

MOSQUITO AND FLY STOP FOR WINDOWS.

1,187,174.

Specification of Letters Patent. Patented June 13, 1916.

Application filed July 28, 1914. Serial No. 853,782.

To all whom it may concern:

Be it known that I, JAMES J. QUINN, a citizen of the United States, residing at 1613 Twelfth street, Eddystone, in the county of Delaware and State of Pennsylvania, have invented new and useful Improvements in Mosquito and Fly Stops for Windows, of which the following is a specification.

10 This invention is an improved stop for use on the under side of an outer window sash to prevent flies and mosquitos from entering the room when the inner sash is raised part way and an ordinary fly screen is arranged below said inner sash, the object of the invention being to provide an improved article of this character which is extremely cheap and simple and which may be readily attached to or detached from the

20 lower side of the upper sash.

The invention consists in the construction and arrangement of devices hereinafter described and claimed.

In the accompanying drawings:—Figure 25 1 is a horizontal sectional view of a window provided with a fly and mosquito stop constructed in accordance with my invention, and looking upwardly. Fig. 2 is a vertical sectional view of the same on the plane indicated by the line 2—2 of Fig. 1. Fig. 3 is a detail perspective view of the stop. Fig. 4 is a detail sectional view of a modified form of the stop. Fig. 5 is a transverse sectional view of the same on the plane indicated by the line 5—5 of Fig. 4.

30 For the purposes of this specification the sides of a window frame are indicated at 1, the outer sash is indicated at 2 and the inner sash is indicated at 3.

40 In accordance with my invention I provide a wiper strip or bar 4 which in the form of my invention shown in Figs. 1—2—3 is made of rubber and in the form of my invention shown in Fig. 4 is formed by 45 a wire screen strip 5. The wiper strip or bar is partly inserted between the upper and lower webs 6—7 of a sheet metal attaching bar 8 which is doubled and bent longitudinally so that a bight 9 is formed between 50 the said web and which presents a rounded outer edge on said attaching bar. The webs 6—7 bear against each other for about halfway across the attaching bar from the outer side, as at 10 and the lower web 7 is

55 offset as at 11 to form a space between said offset portion and the upper web 6 for the reception of the wiper strip or bar 4. The attaching bar is provided with openings for the reception of screws or other like devices 13 by means of which the attaching bar is 60 secured to the lower side of the bottom bar of the upper, outer sash 2 so as to cause the inner edge of the inwardly extending wiper strip 4 to bear against the glass pane 14 of the inner sash. Hence the space between 65 the sashes, when the lower sash is raised and a fly screen is placed thereunder, is closed by the wiper strip 4 and entrance of flies, mosquitos and other noxious insects is effectually prevented.

70 My improved fly and mosquito stop is extremely cheap and simple, is entirely effective and may be readily attached to or removed from a window.

In the form of my invention shown in 75 Figs. 4—5 the attaching bar comprises a central portion 8^a and end members 8^b which are telescopically related thereto and may be adjusted to enable the bar to fit a window sash of any width.

80 Having thus described my invention, I claim:—

1. An insect excluding attachment for windows consisting of a plurality of telescopic frame bars, means for securing said bars to the lower edge of an outer window sash, flexible strips connected within said bars and having the free edges thereof in engagement with the pane of an inner window sash.

90 2. An insect excluding attachment for windows consisting of a plurality of adjustable frame bars, said bars comprising a central section having end sections telescoping therein, means for fastening said bars to the lower edge of an outer window sash, reticulated strips having the inner edges thereof secured to overlapping portions of said bars, and having the free edges thereof normally in contact with the glass pane of a 95 operating sash.

100 In testimony whereof I affix my signature in presence of two witnesses.

JAMES J. QUINN.
